UNITED STATES PATENT OFFICE.

ERNEST H. JACOBS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

FUSE AND MOUNTING.

Application filed May 22, 1919. Serial No. 298,905.

To all whom it may concern:

Be it known that I, ERNEST H. JACOBS, a citizen of the United States, residing in Chicago, in the county of Cook and State of Illinois, have invented a certain new and useful Improvement in Fuses and Mountings, of which the following is a full, clear, concise, and exact description, reference being had to the accompanying drawings, 10 forming a part of this specification.

My invention relates to electrical fuses and mountings for the same.

The aim of the invention is to provide an improved fuse and mounting of such character that the fuse may be readily inserted and withdrawn from the mounting and which fuse is so constructed that it takes the place of a disconnecting switch.

The fuse which I have illustrated in the accompanying drawings is of the expulsion type but it is to be understood that the construction which I have devised is useful not only for fuses of the expulsion type, but of any other type.

In order to secure suitable contact between the terminal of the fuse and the terminals of the circuit, it is customary to provide suitable contacts such as ferrules or blades mounted on the barrel or casing of the fuse and to have these engage suitable spring jaws forming the stationary circuit terminals.

When the contacts are of relatively large size as where considerable current must be carried, and particularly where relatively high tension current is involved, the matter of inserting the fuse into the terminals of the circuit presents a very considerable practical difficulty. As it is necessary to handle a fuse with some kind of implement having a high insulation value, and as the frictional resistance of the terminals is fairly high, taking out or inserting a fuse is awkward and laborious. Particularly is it true where the fuse is fairly long or heavy.

According to my invention I provide a pair of trunnions at one end of the fuse. These trunnions are formed upon the sleeve or barrel and are preferably integral with the lower ferrule. The trunnions are adapted to seat in suitable bearings which preferably are split to permit insertion of and withdrawal of the trunnions. The split bearings are spring pressed to close yieldably upon the trunnions and to make elec-

trical contact therewith. In some embodiments of my invention I arrange the fuse member or some part connected with the trunnions to force the split bearings open upon rotation of the fuse about the trunnions in the bearings. The split bearings preferably have spring means so arranged that the movable portion of the bearings snaps into and out of position automatically.

For convenience in handling the fuse is provided at each end with a ring in such position that the ring which is required is brought into position at the corresponding stage of insertion or withdrawal. To apply or withdraw the fuse I employ a stick or hook such as is well known for use in connection with the operation of disconnecting switches.

I believe I am the first to provide a fuse which is adapted to be thus manipulated by the usual switch stick.

In order to acquaint those skilled in the art with the nature and the manner of practicing my invention I shall now describe the same in connection with the accompanying drawings which illustrate several embodiments of the same.

Figure 1 is a side elevational view of a construction of fuse and mounting which embodies my invention;

Figure 2 is a similar side elevational view on a larger scale, showing a modification;

Figure 3 is a plan view of the same;

Figure 4 is a cross sectional view taken on the line 4—4 of Figure 2;

Figure 5 is a fragmentary sectional view taken on the line 5—5 of Figure 4;

Figure 6 is a side elevational view of a modification;

Figure 7 is a fragmentary side elevation showing the lower terminal and bearing in the open position to permit removal of the fuse;

Figure 8 is a side elevational view of a further modification; and

Figure 9 is a perspective view of the stick or operating implement for withdrawing or inserting the fuse.

The body of the fuse 1 comprises a sleeve or piece of tubing 2, made of suitable insulating material such as fibre, bakelite, hard rubber, glass or the like, having ferrules 3 and 4 screw threaded upon the upper and lower ends respectively of the tube or sleeve. The upper sleeve 3 is provided at its lower

end with an integral petticoat member 5 which serves to keep the adjacent part of the sleeve dry and thus prevent any film of moisture which might tend to form. A 5 ring or lug 6 is formed integral with the petticoat member 5, this ring having a suitable opening or eye 7 which when the fuse is in the position shown in Figure 2, projects forward in the most convenient position to be engaged by the stick or operating implement 8 shown in Figure 9.

The lower ferrule 4 similarly has an integral ring or lug 9 which has the eye 10 also adapted on proper occasion to be engaged by the stick 8.

The ferrule 3 has its outer end closed by the wall 11 as shown in Figure 2, this wall having a perforation thru which passes the fusible link 12, this fusible link being 20 preferably a wire of suitable metal having its outer end clamped under the washer 13 by means of the cap screw 14. It will be seen that the washer 13 is suitably cut away in order that it will not project beyond the 25 edges of the ferrule 3, but at the same time it will shield the opening 15 in the upper wall 11 of the ferrule 3.

At its lower end the fuse wire 12 is clamped between the cap screw 16 and a suitable 30 lug 17 formed on the lower ferrule 4. The ferrule 4 is open at its outer end so that the fuse wire 12 upon being blown may discharge the heated gases and vapors out of the lower end of the sleeve or tube 2, thus 35 extinguishing the arc which would otherwise tend to maintain itself between the terminals.

The lower ferrule 4 is provided with the trunnions 18, which extend laterally in such a manner as to cause the fuse when swung 40 about the axis of these trunnions to move in substantially a vertical plane. These trunnions 18 are preferably formed integral with the lower sleeve 4 and are machined off to give a good cylindrical bearing surface 45 which will form the required contact with the terminal to conduct the current passing thru the fuse. The trunnions 18 are mounted in a split bearing formed of the stationary portion 19 and the movable portion 20. The 50 stationary portion 19 is formed in the shape of a bracket having the cylindrical seat 21 adapted to fit the contour of the trunnion 18. This bracket has the base portion 22, which is mounted upon a suitable support, preferably 55 insulating the same from the surrounding conductor. The stationary member 19 is duplicated so that both trunnions are given proper support, but it is to be understood that this is the preferred manner and 60 not necessarily the only manner in which rotatable support for the fuse could be secured. The ring 9 is placed centrally with respect to the trunnions, so that the handling of the fuse in inserting the same and 65 withdrawing the same, will be greatly sim-

plified. The movable bearing portions 20 are connected together by the cross bar 23 which is cast integral with these bearing portions so that the two parts together form a U-shaped member reaching around the ferrule 4. The stationary bearing portions 19, together with the base portion 22, form a similar U-shaped member and these two U-shaped members are hinged or pivoted together on the shaft 25.

The movable bearing portions 20 are provided with rearwardly extending lever arms 26 which engage springs 27 seated in suitable sockets 28. The outer ends of the bearing portions 19 and 20 on each side are flared outwardly both in order to guide the trunnions into place between the bearing portions and also to guide the ferrule 4 between the bearing portions on opposite sides of the device. The upper or movable bearing portions 20 are provided with seats or sockets 29, which fit closely about the trunnions 18 to secure as large an area of contact as possible.

The upper ferrule 3 is adapted to engage 90 a spring contact terminal formed of two similar flat springs 30 and 31 which are flared outwardly at their outer ends to guide the ferrule 3 between them, and which are provided with curved portions 32 for forming a large area of contact between the springs and the ferrule 3. At their inner ends the springs 30 and 31 are clamped by means of the bolts 33 against a lug or terminal bracket 34 which is formed integral 95 with the base 35. The lug 34 has a finger 36 which extends up and over the ferrule 3 when the fuse 1 is in position.

As shown in Figure 1 the terminals for the fuse 1 are mounted by means of the terminal bases 35 and 22 upon suitable angle brackets 37 and 38. These angle brackets are supported in this case upon the tops of the inclined insulators 39 and 40, these insulators being of any known or preferred 110 type.

The character of the insulating mounting is not of the essence of the present invention and is shown merely to illustrate the usual manner in which fuses of this type are 115 mounted and to make clear the conditions of operation encountered.

The operation of the device shown in Figures 1 to 3 inclusive is as follows: To remove the fuse from the position shown in Figure 1 the finger 42 of the stick or implement 8 is inserted in the eye 7 at the upper end of the fuse and this end of the fuse is pulled outwardly to disengage the ferrule 3 from the spring jaws 30-31. The fuse 1 is then swung down into the dotted line position shown in Figure 1 and the pin 42 of the stick 8 is withdrawn. The rotation of the fuse 1 about the trunnions 18 brings the ring 9 from the position at the rear to 120 125 130

the position at the front as indicated in the dotted line position on Figure 1 and on Figure 2. The operator then inserts the pin 42 in the ring 9 and withdraws the trunnions 5 18 from the spring jaws 19 and 20.

To facilitate the withdrawal of the trunnions 18 from the jaws 19 and 20 I have provided the small cams 43 on the trunnions and have provided co-operating projections 10 44 on the movable jaws 20. Movement of fuse to the position indicated in dotted lines in Figure 2 will rotate cam 43 into the position shown in Figure 5 engaging projections 44 and raising jaws 20. This permits the 15 trunnions 18 to be withdrawn more readily, but it is to be understood that this is a modification which does not depart from the fundamental idea shown in Figures 1, 2 and 3.

20 When it is desired to insert a fuse in the terminals the pin 42 is first placed in the eye 10 and the trunnions 18 are then forced between the spring pressed jaws 20 and 19. The pin 42 is then withdrawn from the eye 25 10 and is inserted in the eye 7 and the fuse 1 is swung upwardly and the upper ferrule 3 is pushed between the spring jaws 30 and 31 to bring the fuse into the position shown in Figure 1.

20 In Figures 6 and 7 I have illustrated a modified form in which the spring jaws are caused to open automatically when the fuse is swung to the inverted position and to close automatically when it is swung to the 35 normal position. The fuse 1 and the upper terminal are of substantially the construction above described. The spring pressed jaws 46 and 47 are pivoted together with the springs 48 arranged to snap the movable 40 jaw 46 open and shut in accordance with the position of the fuse 1. The stationary jaw 47 is provided with an upwardly projecting portion 49 which is adapted to hold the trunnion 18 against outward motion 45 while the movable jaw 46 is being snapped into or out of holding position. The jaw 46 is duplicated for both sides of the fuse and the two parts are connected together evenly by a rod 50, or they may be cast in 50 one piece with a bridge member between them for insuring the joint operation of both arms 46. The movable jaws and stationary jaws are pivoted together upon a shaft 51. The spring 48 is mounted between 55 suitable studs 52 and 53, the stud 53 being mounted in the stationary base portion 54 and being substantially in line with the shaft 51. The stud or projection 52 is adapted to be swung from one side of center to 60 the other with respect to the shaft 51 so that the operation of holding the jaws open or shut may be automatically performed by swinging the fuse about the trunnions 18.

When it is desired to withdraw the fuse, 65 the pin 42 is inserted in the eye 7 and the

fuse 1 is swung about the trunnions 18 into the position shown in Figure 7. In doing so the lower end of the ferrule 4 engages the cross member 50, swinging the movable jaws 46 about the shaft 51 until the spring 70 48 presses on the opposite side of center or in such a direction as to tend to swing the movable arms 46 upwardly. A suitable stop 56 is provided for limiting the motion of these arms 46 to such a position where the 75 arm may again be forced downwardly upon proper operation of the device.

When the parts are in the position shown in Figure 7 the pin may then be inserted in the eye 10 and the fuse may be lifted 80 from the stationary jaw 47 without any difficulty. When it is desired to insert the fuse in the jaws the fuse is first hung upon the stationary jaws 47 as shown in Figure 7, the pin of the stick is then inserted in the eye 7 and the fuse 1 is swung upwardly. In thus swinging upwardly the lower edge 57 of the ring 9 engages the cross bar 50, forcing the same downwardly until the spring is thrown on the opposite side of center, 90 whereupon the movable jaw 46 will be thrown down upon the trunnion 18.

It will be noted that the shape of the end of the jaw 46 is such as to cause the jaw to wedge the trunnion 18 between the portion 49 of the stationary jaw and the edge or end surface 58 of the movable jaw 46. The continued rotation of the trunnion 18 tends further to bind these parts closely together so that very intimate contact is secured. 95

In Figure 8 I have shown a further modification in which the fuse 1 is constructed at its upper end substantially as previously described, but the lower ferrule 60 is formed 105 of greater length in order to engage the spring terminal jaws 61. The trunnions 18 are mounted in suitable brackets 62, which have suitable bearing portions 63. The brackets 62 and the spring jaws 61 are 110 mounted upon a common base 64 which forms the terminal for the lower end of the fuse.

The operation of this form of the device is apparent from Figure 8. The fuse may 115 be withdrawn by inserting the pin 42 in the eye 7 and thereby withdrawing the upper ferrule 3 from contact with the spring jaws 30-31. The lower ferrule 60 is thereafter disconnected from the terminal 61 and the fuse is swung down to inverted position. The pin 42 may then be inserted in the eye 10 and the fuse lifted so that the trunnions come out of the socket portion 63.

In each of the forms shown the fuse 1 is 125 self-supporting and is provided at its lower end with a trunnion or trunnions engaging suitable bearing portions, the trunnions being adapted to be inserted in the stationary bearings by means of the eye or lug secured 130

to the adjacent end of the fuse. The other end of the fuse is then connected by swinging the fuse about the trunnions by means of an eye or lug fastened to the other end of the fuse.

The fuse shown is of the expulsion type and I have therefore provided the finger 36 extending above the top of the upper ferrule. In case of blowing of the fusible wire 10 the finger prevents upward movement of the fuse due to the recoil caused by the explosion.

The particular commercial utility of this device will be apparent from the above description. It will also be appreciated that the device shown and described serves as a combined fuse and disconnecting switch, thereby eliminating the usual disconnecting switch which is necessary where a fuse is 20 employed.

I do not intend to be limited to the precise details of construction shown and described.

I claim:

- 25 1. In combination, a fuse having a sleeve, a contact at one end of the sleeve, a lug projecting forward from said contact, a stationary spring contact member for engaging said contact, a trunnion member mounted on 30 the other end of the sleeve, a stationary bearing member for mounting the trunnion and a lug on said sleeve projecting from the rear of said trunnion member.
2. In combination, a fuse having a sleeve, 35 a contact at one end of the sleeve, a stationary spring contact member for engaging said contact, a trunnion member mounted on the other end of the sleeve, a stationary bearing member for mounting the trunnion and 40 delivering current thereto, said stationary bearing member comprising a pair of spring pressed members for engaging the said trunnion member.

3. In combination, a pair of contact and 45 terminal jaws, one of said jaws moving vertically to receive a trunnion member, a fuse member having a trunnion member adapted to be engaged by said jaws, and a pair of terminal jaws lying at right angles to the first pair of terminal jaws for engaging the 50 opposite end of the fuse.

4. In a device of the character described, 55 a fuse having a self-supporting sleeve, a terminal member at one end thereof, a projection mechanically connected thereto, a trunnion member mounted on the opposite end of the sleeve, a support for said trunnion, and a second projection connected to said trunnion member for mounting and removing 60 the trunnion member on its support.

5. A fuse comprising a sleeve of insulation, a ferrule mounted on the upper end of the sleeve, said ferrule being provided with means to substantially close the upper end 65 thereof and having an integral petticoat

member at its lower end and a projection connected to said petticoat member.

6. In combination, spaced fixed supports, a combined connector and fuse having one end open and the other closed, removably associated with said supports, the closed end of said fuse having a rigid end abutment with the support associated therewith to take the end thrust when the fuse blows and the open end being pivoted to permit the closed end to be swung out from under said end abutment.

7. In a device of the class described, a rigid sleeve having a ferrule member secured thereto at each end and a eye member 80 for each ferrule member, said eye members lying on opposite sides of said sleeve and a pivot between them.

8. In combination, a fuse having a trunnion member, a pair of jaws comprising a 85 relatively stationary jaw and a relatively movable jaw, a spring for the relatively movable jaw, said jaw having means adapted to be engaged by the trunnion member to move said relatively movable jaw against 90 said spring means to permit withdrawal of the trunnion member.

9. In a combined fuse and disconnecting switch, a fuse member having pivotal mounting means at one end thereof, contact means at the opposite end thereof, frictional engaging means for said contact means and yieldable bearing means for mounting said pivotal means and to deliver current thereto, said bearing means being 100 adapted to release the pivotal means bodily.

10. In a combined fuse and disconnecting switch, a fuse member having pivotal mounting means at one end thereof, contact means at the opposite end thereof, frictional engaging means for said contact means, yieldable bearing means for mounting said pivotal means, and an engaging eye 105 at each end of said fuse member for manipulating said fuse.

11. In a combined fuse and disconnecting switch, a sleeve of insulation, metallic terminal members at each end of said sleeve, a fusible link in said sleeve connecting said terminal members, pivotal means extending laterally from one terminal member, stationary mounting means receiving said pivotal means and permitting withdrawal thereof outwardly, and stationary contact means for engaging the other terminal 115 member.

12. In a combined fuse and disconnecting switch, a self-supporting sleeve of insulation, metallic terminal members at each end of said sleeve, a fusible link in said sleeve connecting said terminal members, pivotal means lying at substantially right angles to the axis of the sleeve, said pivotal means being mounted upon one of the terminal members, spring pressed jaw members for 125 130

- gripping said pivotal means, stationary contact means lying at substantially right angles to the pivotal means for engaging the upper terminal member, and an eye connected to each terminal member. 50
13. In combination, a pair of spring jaws adapted to have a member moving in a vertical plane inserted between them, a second pair of jaws adapted to have a horizontal bearing member gripped between them, and a fuse having an upper terminal member adapted to engage the spring jaws and having a lower terminal member provided with a trunnion adapted to lie between the second pair of jaws. 10
14. In combination, a pair of jaws adapted to grip a member swinging in one plane, a second pair of jaws adapted to engage a rotary member lying in a plane substantially at right angles to said first plane, a fuse member having a terminal adapted to move in said first plane, and having a trunnion member and terminal having its axis at substantially right angles to said first plane, said trunnion member being engaged by said second pair of jaws. 20
15. In combination, a pair of jaws, one of said jaws being movable, spring means for moving said jaws either away from or towards the stationary jaw, a fuse having a terminal member comprising a trunnion adapted to be gripped between the stationary and the movable jaws, and having means for moving said movable jaw at the center with relation to said spring means in either direction upon rotation of the fuse about said trunnion member. 30
16. In combination, a fuse having a sleeve, a ferrule mounted on the lower end of the sleeve, said ferrule having a pivot for mounting the fuse and having a projection connected thereto for removal or insertion of the pivot of the fuse from or into its mounting. 40
17. In combination, a fuse having a sleeve, ferrules on each end of the sleeve, trunnions projecting laterally from one of said ferrules, jaw members for yieldably gripping said trunnions, stationary contact means for engaging the other said ferrule, and a finger for engaging the upper end of said last mentioned ferrule lying above the stationary contact. 50
18. In combination, a fuse having a sleeve, contact members on each end of the sleeve, a stationary terminal member for engaging the upper contact member, a pair of spring pressed jaw members forming the terminal for the lower contact member, pivotal means on the lower contact member engaged by said spring pressed jaw members, and means on said pivotal means for opening the jaw members as the fuse is swung into lower position for removal. 60
19. In combination, a fuse having a sleeve, contact members on each end of the sleeve, one of said contact members being adapted to be engaged by a terminal member, the other of said contact members being adapted to have pivotal spring pressed engagement with a second terminal member, and means for releasing said spring pressed engagement to permit removal of the fuse. 70
20. In combination, a fuse having a sleeve, contact members at each end of the sleeve, one of said contact members being adapted to be engaged by a terminal member, the other of said contact members being adapted to have pivotal spring pressed engagement with a second terminal member, 75 means for releasing said spring pressed engagement as the said first contact member disengages its cooperating terminal member, and means adjacent said pivotal engagement for permitting removal and replacement of the fuse. 80
21. In combination, a removable fuse comprising a sleeve of insulation carrying an upper contact member and a lower contact member each adapted for cooperation with stationary contacts, eyes secured to the contacts upon opposite sides of the fuse whereby one contact must be released and the fuse swung about the other contact before the eye of the other contact is accessible. 85
22. In combination, a removable fuse comprising a sleeve of insulating material, an upper contact and a lower contact on the sleeve, stationary terminals cooperating with the contacts, said lower terminal comprising a bearing, the lower contact on the fuse having a pivot cooperating with said bearing, an eye lying in front of the upper contact for separating the contact from its terminal and an eye lying back of the lower contact for separating the pivot from said bearing. 100
23. In combination, a fuse having a trunnion, a terminal having a bearing and an eye lying on the fuse adjacent the trunnion for removal of the trunnion from the bearing. 110
24. In combination, a fuse having upper and lower contacts, upper and lower terminals, one of said contacts comprising a pivot and the cooperating terminal comprising a bearing, said pivot and bearing being readily separable regardless of the angular position of the fuse. 115
25. In combination, spaced fixed terminals, a connecting element pivotally and removably associated with one terminal at one end, and removably associated at the other end with the other terminal, pulling means adjacent said last mentioned and accessible when the element is in operative position, and pulling means adjacent said one end, moved into accessible position by opening the circuit at the other end. 120
26. In combination, spaced fixed termi. 125

nals, a connecting element removably associated with both terminals, and two different pulling means for removing said element from the terminals, one pulling means being relatively inaccessible when the element is in operative position to compel removal of said element from a predetermined terminal first.

27. In combination, spaced fixed terminals, a connecting element removably associated with both terminals, and pulling means adjacent each terminal, movement of said element into operative association with one terminal shifting the other pulling means into inaccessible position.

15 28. In combination, a combined fuse and switch connecting element, a switch support having removable pivotal connection therewith and delivering current thereto, and another terminal spaced from this support for engagement with the remote end of the fuse, removal of the fuse from the last mentioned terminal positioning the fuse so as to be readily lifted away from said support.

29. In a combined fuse and disconnecting switch, a sleeve of insulation, metallic terminal members at each end of said sleeve, a fusible link in said sleeve connecting said terminal members, pivotal means extending laterally from one terminal member, stationary mounting means receiving said pivotal means and permitting withdrawal thereof outwardly, stationary contact means for engaging the other terminal member, a pulling eye on the outer side of said last mentioned terminal member, and a pulling eye on the inside of said first mentioned terminal member.

30. In combination, spaced fixed supports, a combined connector and fuse having one end open and the other closed, removably associated with said supports, the closed end of said fuse having end abutment with the support associated therewith to take the end thrust when the fuse blows, said closed

end being removable by movement perpendicular to the axis of said fuse.

31. A fuse member having a metallic ferrule at each end, and an eye member for each ferrule, and a pivot member for one ferrule, the eye for said ferrule lying on the back of the pivot.

32. A fuse member having a metallic ferrule at each end, and eyes connected to said ferrules on opposite sides of the sleeve, one of the ferrules having means for mounting 55 the same pivotally.

33. In combination, stationary contacts comprising an upper slip contact, a lower pivot contact, a fuse having an upper slip ferrule and a lower pivot ferrule, and an eye on the front side of the slip ferrule and an eye on the back side of the pivot ferrule.

34. In combination, stationary contacts comprising an upper slip contact, a lower pivot contact, a fuse having an upper slip ferrule 65 and a lower pivot ferrule, and an eye on the front side of the slip ferrule and an eye on the back side of the pivot ferrule, and a stationary abutment lying above the upper terminal in position to overlie the upper end 70 of the upper terminal when the fuse is in place.

35. A fuse having an upper slip ferrule and a lower pivot ferrule, an eye on the front side of the slip ferrule and an eye on 75 the back side of the pivot ferrule.

36. The combination, stationary contacts, a fuse member having a sleeve of insulation bearing ferrules at opposite ends, said ferrules and contacts having co-operating configuration controlling the position of the fuse, and eyes on the ferrules lying on opposite sides of the fuse in the plane of movement of the fuse into and out of the contacts.

In witness whereof I hereunto subscribe my name this 13 day of April, A. D. 1919.

ERNEST H. JACOBS.
